CLAIM

The ornamental design for a strobe light, as shown and described.

DESCRIPTION

FIG. 1 is a front plan view of a strobe light.

FIG. 2 is a back view thereof.

FIG. 3 is a left side view thereof.

FIG. 4 is a right side view thereof.

FIG. 5 is a top view thereof.

FIG. 6 is a bottom view thereof.

FIG. 7 is a first perspective view thereof.

FIG. 8 is second perspective view thereof.

FIG. 9 is a third perspective view thereof; and,

FIG. 10 is a fourth perspective view thereof.

The broken line showing represents portions of the article not claimed and forms no part of the claimed design.

1 Claim, 7 Drawing Sheets(56)
